Primary Examiner — Catherine Ho(74) *Attorney, Agent, or Firm* — SERVILLA WHITNEY LLC(57) **CLAIM**

The ornamental design for a medical device label, substantially as shown and described.

DESCRIPTION

FIG. 1 is top front isometric view of a medical device label; FIG. 2 is a top view of the medical device label; FIG. 3 is bottom view of the medical device label; FIG. 4 is a left side view of the medical device label; FIG. 5 is a right side view of the medical device label; FIG. 6 is a front view of the medical device label; FIG. 7 is a rear view of view of the medical device label; and,

FIG. 8 is a top front isometric view of the medical device label of FIG. 1 shown in an environment of use.

The syringe shown in broken lines in FIG. 8 illustrates environmental structure and forms no part of the claimed design. All other broken lines show portions of the article and forms no part of the claimed design.

1 Claim, 5 Drawing Sheets(56)
